Primary Examiner — Jack Reickel*Assistant Examiner* — Sydney M Evans(74) *Attorney, Agent, or Firm* — Westbridge IP LLC(57) **CLAIM**

The ornamental design for a magnetic snap for a screen door, as shown and described.

DESCRIPTION

FIG. 1 is a top perspective view of a magnetic snap for a screen door showing my new design;

FIG. 2 is a front elevation view thereof;

FIG. 3 is a rear elevation view thereof;

FIG. 4 is an enlarged left side elevation view thereof;

FIG. 5 is an enlarged right side elevation view thereof;

FIG. 6 is a top plan view thereof;

FIG. 7 is a bottom plan view thereof;

FIG. 8 is an exploded top perspective view thereof;

FIG. 9 is an enlarged sectional view taken along line 9-9 of FIG. 2; and,

FIG. 10 is a partial enlarged view taken from circle 10 of FIG. 9.

The dot-dash broken lines in the drawings are included for the purpose of depicting the partial enlarged views.

The dash-dash broken lines in the drawings indicate the plane upon which a sectional view is taken and form no part of the claimed design.
